UNITED STATES PATENT OFFICE.

WILLIAM ALFRED HAYWOOD, OF DENVER, COLORADO.

SHADE.

SPECIFICATION forming part of Letters Patent No. 690,725, dated January 7, 1902.

Application filed September 24, 1901. Serial No. 76,425. (No model.)

To all whom it may concern:

Be it known that I, WILLIAM ALFRED HAYWOOD, a citizen of the United States, and a resident of Denver, in the county of Arapahoe and State of Colorado, have invented new and useful Improvements in Shades, of which the following is a full, clear, and exact description.

This invention relates to a shade adapted to be applied to one's hat, so that the wearer 10 may be shaded from the sun. The device is constructed so that it may readily be folded when not in use.

This specification is a specific description of one form of my invention, while the claims 15 are definitions of its actual scope.

Reference is to be had to the accompanying drawings, forming a part of this specification, in which similar characters of reference indicate corresponding parts in all the figures.

20 Figure 1 is a perspective view of a hat having my invention applied. Fig. 2 is a bottom plan view of the shade; and Fig. 3 is a view of the shade, showing the shade folded.

The shade is made up of a folding frame, 25 preferably of wire, on which is arranged a fabric covering. The frame comprises two pairs of bars 4, the members of each pair of which are pivoted together, as indicated at 5. These pairs of bars 4 are joined together by

30 the eyepins 6 at each side, as indicated in Fig. 2. The bars 4 thus arranged are capable of folding in an approximate parallelism by moving around their pivots 5, and the pairs of bars are capable of swinging toward each other on centers located at the eyepins 6. Fastened to the pivots 5 are bars 7, which project longitudinally oppositely from each other toward the ends of the shade, and arranged at the side of the shade in connection 35 with each eyepin 6 are bars 8, which are two at each side.

9 represents the fabric covering, which is fastened to the inner parts of the bars 4 and connected to the outer ends of all of the bars 45 4, 7, and 8. This connection may be effected by any means desired—for example, by means of the eyes in the pins, as indicated at 10 at the right-hand side of Fig. 2.

The arrangement of the bars 4 is such that 50 in the center of the shade when extended there is left an open space capable of receiving the crown of a hat in the manner indicated in Fig. 1. For this purpose the inner ends of the bars 4 are bowed slightly, as illustrated.

The shade when extended, as in Figs. 1 and 2, may be conveniently placed over the crown of a hat and will afford ample shade to the wearer. When it is desired to fold the shade, assuming that the shade be held with the bottom side up, as in Fig. 2, the bars 8 should first be turned downward on the line *a a* in Fig. 2. Then the bars 4 should be turned together or toward each other on the line *b b*, Fig. 2. When this is done, the bars 4 may 65 be turned on their pivots 5, so as to lie against each other approximately in the line *c c*, Fig. 2.

For facilitating the folding operation the cloth or fabric 9 on the bars 4 adjacent to the pivots or eyepins 6 may be turned down, leaving the bars bare, as shown in Fig. 3. For permitting this operation the cloth should be joined to the bars by casings formed in the cloth. (See Fig. 2.)

I wish to explain that the particular forms 75 of the various bars and the hinged connection between them are not essential to my invention. The construction here shown I consider to be best adapted to the end in view; but I do not limit myself to the precise arrangement shown.

Having thus described my invention, I claim as new and desire to secure by Letters Patent—

1. A shade comprising a frame formed of 85 two pairs of bars, the members of which pairs are pivotally connected together intermediate their ends, the said pairs of bars being pivotally connected together at their inner or adjacent ends, a side bar located at each side 90 of the said pairs of bars and extending outward therefrom, and a fabric covering on the bars.

2. A shade comprising a folding frame formed of two pairs of bars, the members of 95 which are pivoted together at their adjacent ends, side bars located at each side of the said pairs of bars and pivotally connected therewith, and end bars connected to the pivot of each of the said pairs of bars, the 100 end bars extended outward oppositely from each other, and a fabric covering held on the frame.

In testimony whereof I have signed my name to this specification in the presence of 105 two subscribing witnesses.

WILLIAM ALFRED HAYWOOD.
